PLAYING CARD

Ernest W. Ekstrand, Santa Ana, Calif.
(240 Chestnut, Apt. 1013, Long Beach, Calif. 90802)

Filed Aug. 19, 1971, Ser. No. 173,354

Term of patent 14 years

Int. Cl. D21—01

U.S. Cl. D34—13

The figure is a plan view of a playing card, showing my new design.

The side not shown is conventional.

I claim:

The ornamental design for a playing card, as shown and described.
